UNITED STATES PATENT OFFICE.

CHARLES E. OLIVER, OF BOSTON, MASSACHUSETTS, ASSIGNOR TO UNIVERSAL SAFETY TREAD COMPANY, OF BOSTON, MASSACHUSETTS, A CORPORATION OF MASSACHUSETTS.

STAIR-TREAD.

1,340,243.

Specification of Letters Patent. Patented May 18, 1920.

Application filed July 27, 1918. Serial No. 246,951.

To all whom it may concern:

Be it known that I, CHARLES E. OLIVER, of Boston, in the county of Suffolk and State of Massachusetts, a citizen of the 5 United States, have invented a new and useful Improvement in Stair-Treads, of which the following is a specification.

My invention relates to metal stair treads and more particularly to treads adapted to 10 be used on board ship or in other places where the stair structure may consist simply of metallic side stringers for the treads and hand rails for the user. In such structures, especially on board ship, it is desirable to have something that is not only light 15 but very strong, able to take a great deal of wear, and also able to carry what is known as a safety or non-slipping tread upon it. My present construction enables the step 20 and tread to be made in one piece and especially by practically one operation.

My invention in its preferred form will be understood by reference to the drawings, in which—

25 Figure 1 is a plan showing my invention in its preferred form,
Fig. 2 being an under view thereof.
Fig. 3 is a front elevation, and
Fig. 4 a longitudinal section on line 4—4

30 of Fig. 1.
Fig. 5 is an end elevation, and
Fig. 6 a cross section on line 6—6 of
Fig. 1,

Fig. 7 showing one end of the blank from 35 which the tread may be made.

Fig. 8 is a small detail showing the way in which the treads are used.

It being understood that the other end of the blank in its preferred form is like that 40 shown in Fig. 7, my invention comprises a face plate A having front and back flanges B and end flanges C, the dotted lines b , b and c , c indicating the lines along which the flanges are bent to form the completed step.

45 It will be noted that the front and back flanges have extensions B^1 , B^1 (see Fig. 7).

The completed step as shown in the other views comprises, also, flanged, transverse braces D, of which three are shown, riveted 50 at d to the face of the step and at d^1 through their end flanges to the flanges B. In the complete steps, also, the extensions B^1 are bent around to engage the flange C and both they and the flange C are provided with 55 openings c^1 by which the tread as a whole

may be attached to the side pieces or stringers F by which the treads are supported. This attachment of the flanges C, reinforced by the overlapping extension B^1 , is preferably effected by bolts c^2 passing through 60 said reinforced flanges C and said side pieces or stringers F, as will be understood from Fig. 8. It will also be noted that the front and back flanges B are wider at the point b^1 than at their end, this extra width giving 65 additional support, after the manner of a girder, to the face of the tread at a point where it would receive the greatest strain, that is, midway between its points of attachment to the stringers. In addition the main 70 plate or face of the step may be provided with a safety tread E comprising flanges e between which an abrasive or non-slipping material may be applied in the usual manner. This construction is so well known 75 that it need not be further described.

Methods of constructing this device will suggest themselves to those skilled in the art, but one advantage of my structure is that the stair tread may be shaped by a single operation from a plate of the character shown in Fig. 7. Each plate may or may not have been provided with flanges e to receive the non-slipping material e^1 . The tread being properly shaped, that is, its 80 flanges B and C being turned down to define the tread proper, the extensions B^1 are next turned at right angles to the flanges B and are then riveted or otherwise attached to the flanges C, or what is simpler, having 85 been provided with suitable holes, the tread as a whole may then be bolted to the side rails. The braces D, when used, are riveted in place.

Drain holes e^2 are preferably provided 90 to prevent the collection of water on the tread.

While other means may be provided for giving to the tread its necessary strength, the form of construction shown and above 100 described enables a comparatively thin sheet metal to be used, from which the tread may be die cut, the flanges B and C giving to the thin face of the tread the necessary strength on the four sides to withstand a 105 very heavy strain, this strength being added to by the braces D.

What I claim as my invention is:—

1. A stair tread comprising a rectangular sheet metal face plate having integral de- 110

pending flanges at each end thereof and also at the front and back thereof, said front and back flanges having integral extensions which are bent around outside of said end flanges and so as to overlap and reinforce the latter.

2. A stair tread comprising a rectangular sheet-metal face plate having integral depending flanges at each end thereof and also at the front and back thereof, said front and back flanges having integral extensions which are bent around outside of said end flanges so as to overlap and reinforce the latter, said front and back flanges being wider at their middle parts than at their ends, to form girder-like supports to front and back of the face plate.

3. A stair tread comprising a rectangular sheet-metal face plate having integral depending flanges at each end thereof and also at the front and back thereof, said front and back flanges having integral extensions which are bent around outside of said end flanges so as to overlap and reinforce the latter, said tread having flanged, transverse braces attached to the face plate and to the front and back flanges to distribute the

strain upon the longitudinal portion of the face plate between its edges.

4. A stairway comprising side pieces or stringers and a series of rectangular stair treads, each of said stair treads consisting of a piece of sheet metal having integral depending flanges at its ends and also at its front and back sides, said front and back flanges having extensions overlapping and reinforcing said end flanges, and attaching bolts passing through said reinforced end flanges and serving to secure the tread to said side pieces or stringers.

5. A stairway comprising side pieces or stringers and a series of rectangular stair treads, each of said stair treads consisting of a piece of sheet metal having integral depending flanges at its ends and also at its front and back sides, said front and back flanges having extensions overlapping and reinforcing said end flanges, each stair tread having a plurality of flanged, transverse braces attached to its under side, and attaching bolts passing through said reinforced end flanges and serving to secure the tread to said side pieces or stringers.

CHARLES E. OLIVER.
